UNITED STATES PATENT OFFICE.

HENRY SCHUMACHER, OF SAN FRANCISCO, CALIFORNIA.

GEOGRAPHICAL CLOCK.

SPECIFICATION forming part of Letters Patent No. 745,680, dated December 1, 1903.

Application filed December 30, 1902. Serial No. 137,096. (No model.)

To all whom it may concern:

Be it known that I, HENRY SCHUMACHER, a citizen of the United States, residing in the city and county of San Francisco, State of California, have invented an Improvement in Geographical Clocks; and I hereby declare the following to be a full, clear, and exact description of the same.

My invention relates to improvements in timepieces whereby the time for any place in the world may be determined instantly and the time of that place noted relative to any other place. It has been usual in the construction of this class of clocks to employ a dial turnable with the hour-hand and on which is mapped a polar projection of the earth or a portion thereof and in relation to which dial is a stationary disk graduated according to the twenty-four hours of the day. The objection to all these clocks is that with the continued rotation of the map it is almost impossible to read the names of places it may be desired to learn about, owing to the fact that the names are upside down half the time, and, furthermore, by reason of the constant change of the position of the places about the central axis the eye does not readily become trained to look in the right direction or to the particular spot to find the locality wanted.

One of the objects of my invention is to provide a clock whereby it will be very simple to locate the various places upon the different meridians and to read the time upon any meridian. To this end I employ a stationary dial having radial division-lines corresponding to certain units of time measurement, between which lines are printed the names of cities lying in any corresponding meridian interval. Concentric with this disk is a revoluble dial making one revolution in twenty-four hours and having the hours marked on weighted disks pivoted to the dial and adapted always to maintain an upright position, so as to be easily read. This dial is movable in relation to a stationary pointer which is set over the city whence time is to be measured.

There are further details which will be more fully set forth hereinafter, having reference to the accompanying drawings, in which—

Figure 1 is a plan view of my invention. Fig. 2 is a section of a weighted hour-disk. Fig. 3 is an elevation of the same. Fig. 4 is 55 a chart for locating various cities.

A represents a stationary disk fixed to the face of the clock-casing concentric with the post 2, which carries the minute-hand 3. A dial 4, carried by a sleeve upon the post, is 60 turnable within an annular area 5 on the disk. The dial 4 is subdivided into twenty-four parts, one half numbered from "1" to "12," the usual subdivisions of time, and representing from midnight to midday, or 65 a. m., the other half numbered from "1" to "12" and representing from noon to midnight, or p. m. The dial makes one revolution in twenty-four hours, while the minute-hand 3 makes one complete revolution every 70 hour. It will be noted that the dial serves all the purposes of an hour-hand, and no hour-hand proper is used. In order to assist in reading the hours, I have shown the latter as numbered on weighted disks 6, pivoted on 75 the dial so as always to stand perpendicular. The dial is in the form of a wheel having a central open space through which the minute-markings on the disk A are visible, as at 7. If desired, the disks 6, corresponding to 80 the hours from six p. m. to six a. m., may be black, while those from six a. m. to six p. m. may be white to contrast night and day. Neon or meridian is indicated by a radial projection 8 on the dial.

The annular space 5 on disk A is subdivided into equal units of time by the radial lines 9. In the present instance these lines are disposed at intervals of fifteen degrees on the circle, corresponding to one hour of time. 90 Each subdivision may be designated successively by a letter, as indicated thus: "A," "B," "C," "D," &c. These subdivisions, it will be seen, may be considered as representing fifteen degrees of longitude as the same 95 would appear on a spherical projection of the earth's surface. Instead, however, of laying out a distorted map of the earth in the annulus 5 I simply print the names of such places falling within any certain meridian interval 100 in a corresponding subdivision of 5. For instance, start from Washington, District of Columbia, as a center. All places lying between seventy-five degrees and ninety degrees lon-

gitude west of Greenwich of which places it may be desired to know the time are printed in division "A" and each city located within that subdivision situated in its correct relative position to the right of the left-hand boundary-line of that division correspondingly with its actual location west of parallel of longitude seventy-five degrees.

10 is a pointer movable independently of the clock mechanism beneath the dial and having a knife-edge portion 10^a movable over the printed surface 5 and adapted to be set at any particular place whence time is to be computed. For illustration, assume the clock 15 to be set up in San Francisco and the San Francisco time at that instant to be 3.20 p.m. The pointer or marker 10 is moved to coincide with San Francisco, and thenceforth it remains in that position, as it is intended 20 mainly as a marker for the particular locality in which the clock is used. The clock is then set by turning the minute-hand to bring the dial 4 with the interval between "3 p.m." and "4 p.m." adjacent to the marker and with 25 the minute-hand pointing at "20" of the minute-markings 7 on disk A. Four o'clock p.m. at San Francisco will be indicated when the minute-hand is at "60" and the dial stands with "4 p.m." in juxtaposition with pointer 30 10. Then to know at an instant what the time is of any other place in the world it is only necessary to glance at the subdivision of 5 in which that place may be and project the time interval indicated on the part of the 35 disk inclosed in the angle of the particular subdivision.

To facilitate the reading of time at any city, I provide the dial 4 with an annular transparent projection 11, extending over 40 the annulus 5 and having radial markings 12, corresponding to hours and sixths or other suitable subdivisions of hours. I use sixths for the reason that it enables me to estimate within ten minutes of the correct time of 45 any place. For example, when it is four o'clock p.m., San Francisco, a glance at Washington shows it to be seven p.m., approximately. London, on the line between subdivisions "S" and "T," will show the time 50 to be 12.10 a.m., approximately.

By providing a chart, as 13, on which the various cities are arranged alphabetically

and placing after each city the letter designating in subdivision on annulus 5 the city can be readily located and the time determined. 55

Having thus described my invention, what I claim, and desire to secure by Letters Patent, is—

1. In a geographical clock, the combination of a stationary disk having an annular area located between its center and outer edge, and a circle interior to the annular space and subdivided radially to units of time representing minutes, said disk having 60 its surface beyond the annular area subdivided into equal units of time by radial lines; a movable dial mounted in the annular area of the disk, and having an open center through which said minute-markings are 65 visible; cities marked within the radial subdivisions of the disk outside of the dial; a rigid pointer pivoted beneath the dial and between the same and the disk, and having a knife-edge portion to move over the surface of the disk; and a minute-hand movable in relation to the dial, said dial serving in lieu of an hour-hand and having its surface subdivided to represent hours. 70

2. In a geographical clock, the combination of a stationary disk having an annular area between its center and outer edge, and having the space between said area and outer edge subdivided radially and arbitrarily designated; a circle interior to the annular area of the disk and subdivided radially to represent minutes; a dial subdivided into hours and rotatably mounted in the annular area of the disk and having an open center to expose the minute-marking thereof; geographical markings in the radial subdivisions exterior to the annular area of said disk; and a pointer located between the disk and dial 85 said dial having an annular transparent peripheral projection extending over the disk 90 and having radial markings corresponding to hours and subdivisions thereof. 95

In witness whereof I have hereunto set my hand.

HENRY SCHUMACHER.
